UNITED STATES PATENT OFFICE.

EMIL A. CHRISTOPH, OF CHICAGO, ILLINOIS, ASSIGNOR, BY MESNE ASSIGNMENTS, TO
THE KING LOCK COMPANY, OF CHICAGO, ILLINOIS, A CORPORATION OF ILLINOIS.

LOCK.

1,204,545.

Specification of Letters Patent. Patented Nov. 14, 1916.

Application filed March 27, 1913. Serial No. 757,086.

To all whom it may concern:

Be it known that I, EMIL A. CHRISTOPH, a resident of Chicago, in the county of Cook and State of Illinois, have invented certain new and useful Improvements in Locks, of which the following is a full, clear, and exact description.

The invention relates to key-controlled locks.

The invention designs to provide a lock which is simple in construction, and which cannot be operated except by a properly formed key.

The invention consists in the several novel features hereinafter set forth and more particularly defined by claims at the conclusion hereof.

In the drawings: Figure 1 is a front view of a lock embodying the invention. Fig. 2 is a rear elevation. Fig. 3 is a section taken on line 3—3 of Fig. 2, the key being shown in position to release the tumblers. Fig. 4 is a similar section, the key being withdrawn. Fig. 5 is a section taken on line 5—5 of Fig. 4. Fig. 6 is a section taken on line 6—6 of Fig. 3. Fig. 7 is a plan of the slotted spindle. Fig. 8 is a section on line 8—8 of Fig. 4.

The lock is shown as secured to a plate 12 and comprises a barrel 13 which is secured to said plate by screws 14. The barrel has a sleeve or hub 13^a extending through plate 12 to form a bearing for the key-spindle 15 which has its front end journaled in hub 13^a and is formed with a head 16 for limiting the spindle against rearward movement in the barrel. A cap 17 is connected by a screw-thread 18 to a screw-thread 19 on the inner end of the spindle and has a flange 20 bearing on the inner end of the cylinder 13 to support the inner end of the spindle. A series of tumbler disks or plates 21 fills the space between the front wall of the barrel and the cap 17. Each tumbler is formed out of a thin strip or sheet of metal and comprises a pair of oppositely disposed projections or teeth 22 and 23 which are adapted to slide radially in grooves 24 on the opposite sides of the spindle. Each tumbler also comprises a circular portion 25 extending around the spindle and a pair of oppositely disposed abutments 26 and 27 which are adapted to pass respectively into slots 28 and 29 in barrel 13 to lock the spindle and the tumblers against rotation. A number of the

foremost tumblers are provided with extensions 30 which fit into a recess 31 in a slidable locking-bolt 32, the operation of which is controlled by the lock. These extensions serve to shift the bolt when the spindle and tumblers are rotated.

A key 33 which is adapted to be inserted into a narrow slot 15^a in the spindle 15, has its opposite edges formed of irregular but corresponding outline, so that its width at all points will correspond to the distance between the abutments 22 and 23 on each tumbler. Key 33 has a groove therein, and the slot 15^a in the spindle is correspondingly formed to guide the key in the spindle. When the projecting edge-portion of the key at one side of the key moves one end of the said tumblers outwardly, the opposite abutment on the same tumbler will be free to move inwardly a correspondingly extent by reason of the parallel-edged key. In this manner, the tumblers are positively shifted and controlled by the key without the use of springs. The tumblers are confined against axial movement between the cap 17 and the front of the barrel 13 by one another. By adjusting the cap on the spindle, the tumblers may be frictionally held together to prevent undesirable freedom of movement thereof.

In making the lock, the tumblers are all stamped of the same shape with abutments 26 and 27 of maximum length. The key will then be made with parallel edges, but of any desired contour. The key, or a form like the key, is then inserted into the desired number of assembled tumblers and with the entire series of tumblers for the lock adjusted to the key, the projecting portions of the abutments 26 and 27 will be cut off on a straight line, so that when the key is in the spindle, all the tumblers will clear the slots 28, 29 in the barrel and be free to rotate in the barrel and operate bolt 32.

In operation, when the bolt 32 is in locking position (Figs. 2 and 4) abutments 26, 27 on the tumblers will be in one of the slots 28, 29 and thus lock the spindle against rotation and bolt 32 against movement. When a key of the correct form is inserted, it will, in passing through the slot in the spindle, shift the tumblers successively, but when the key is fully inserted, all the tumblers will be relatively disposed and held so all the outer ends of abutments 26 and 27

- will be alined and be clear of slots 28 and 29. The key may then be rotated to turn the spindle, and tumblers and cause arms 30 to shift bolt 32. The lock shown is adapted for use where the key is not to be removed when bolt 32 is unlocked. When the key is turned back to bring the abutments 26, 27 in registry with slots 28, 29, the key may be withdrawn. During withdrawal of the key, its projecting edges will relatively shift the tumblers radially and positively and insure entry of the abutments into the slots, and thus lock them and the bolt 32 against movement.
- 15 The invention thus exemplifies a lock in which the use of spring-operated tumblers is entirely avoided and in which a very slight variation in contour of the key will make it impossible to operate the lock therewith.
- 20 The manner of making and construction of the tumblers make it practical to use very thin metal, if desired. These tumblers can be very cheaply made with their abutments alike and then exactly sized according to the
- 25 keys by placing a key or form in the assembled tumblers, formed for holding them in associated relation and then moving or cutting off the abutments. The lock is exceedingly simple in construction.
- 30 The invention is not to be understood as restricted to the details set forth, since these may be modified within the scope of the appended claims without departing from the spirit and scope of the invention.
- 35 Having thus described the invention, what I claim as new and desire to secure by Letters Patent, is:
1. A lock comprising a spindle having a key way therein, a series of rotatable tumbler plates provided with a pair of oppositely disposed abutments adapted respectively to normally engage the spindle and be engaged by a key to shift the tumblers in the opposite directions and locking means on the tumblers.
  2. A lock comprising a spindle having a key way therein, a series of rotatable tumbler plates provided with a pair of oppositely disposed abutments adapted respectively to normally engage the spindle and to be engaged by a key to shift the tumblers in opposite directions and locking abutments on the tumblers varying in length in accordance with the contour of the key, so that when the key has been inserted in the spindle, the ends of the locking abutments will be alined whereby the spindle and plates may be rotated.
  3. A lock comprising a spindle having a key way therein, a series of rotatable tumbler plates provided with a pair of oppositely disposed abutments adapted respectively to normally engage the spindle and to be engaged by a key to shift the tumblers in opposite directions, means for holding the

plates in face to face engagement, and locking-means on the tumblers.

4. A lock comprising a spindle having a key way therein, a series of rotatable tumbler plates provided with a pair of oppositely disposed abutments adapted respectively to normally engage the spindle and to be engaged by a key to shift the tumblers in opposite directions, means for holding the plates in face to face engagement and locking-abutments on the tumblers varying in length in accordance with the contour of the key so that when the key has been inserted in the spindle, the ends of the locking abutments will be alined, whereby the spindle and plates may be rotated. 70

5. A lock comprising a spindle having a key way therein, a series of tumbler plates provided with a pair of oppositely disposed abutments engaging the spindle and adapted 75 respectively to be engaged by a key to shift the tumblers in opposite directions, said plates being cut away to pass around the spindle and being held against rotation relatively to the spindle, and locking means on the tumblers. 80

6. A lock comprising a spindle having a key way therein, a series of tumbler plates provided with a pair of oppositely disposed abutments engaging the spindle and adapted 85 respectively to be engaged by a key to shift the tumblers in opposite directions, said plates being cut away to pass around the spindle and being held against rotation relatively to the spindle, and locking abutments 90 on the tumblers varying in length in accordance with the contour of the key so that when the key has been inserted in the spindle, the ends of the locking abutments will be alined. 95

7. A lock comprising a spindle having a key way therein, a series of tumbler plates provided with a pair of oppositely disposed abutments adapted respectively to be engaged by a key to shift the tumblers in opposite directions, said spindle having longitudinal grooves therein in which said abutments are radially movable, the abutments serving to connect the spindle and plates for rotation, and locking means on the tumblers. 100 105

8. A lock comprising a spindle having a key way therein, a series of tumbler plates provided with a pair of oppositely disposed abutments adapted respectively to be engaged by a key to shift the tumblers in opposite directions, said spindle having longitudinal grooves therein in which said abutments are radially movable, the abutments serving to connect the spindle and plates for rotation, and locking abutments on the tumblers varying in length in accordance with the contour of the key, so that when the key has been inserted in the spindle, the ends of the locking abutments will be alined. 110 115

9. A lock comprising a fixed barrel, a 110 120 125

spindle in the barrel and having a key way therein, a series of rotatable tumbler plates provided with a pair of oppositely disposed abutments adapted respectively to normally engage the spindle and to be engaged by a key to shift the tumbler plates in opposite directions, locking means on the tumbler plates comprising abutments for engaging the barrel to secure the plates against rotation, and means for holding the plates in face to face engagement in the barrel.

10. A lock comprising a fixed barrel, a spindle in the barrel and having a key way therein, a series of rotatable tumbler plates 15 provided with a pair of oppositely disposed abutments adapted respectively to be engaged by a key to shift the tumbler plates in opposite directions, locking means on the tumbler plates comprising abutments for engaging the barrel to secure the plates against rotation, grooves in the spindle in which the oppositely disposed key-engaged abutments 20 are slidably radially and means for holding the plates in face to face engagement in the 25 barrel.

11. A lock comprising a fixed barrel, a spindle in the barrel and having a key way therein, a series of rotatable tumbler plates provided with a pair of oppositely disposed abutments adapted respectively to normally engage the spindle and to be engaged by a key to shift the tumbler plates in opposite directions, locking means on the tumbler plates comprising oppositely disposed abutments for engaging the barrel to secure the plates against rotation, and means for holding the plates in face to face engagement in the barrel.

12. A lock comprising a fixed barrel, a
40 spindle in the barrel and having a key way
therein, a series of rotatable tumbler plates
provided with a pair of oppositely disposed
abutments adapted respectively to be en-
gaged by a key to shift the tumbler plates
45 in opposite directions, locking means on the
tumbler plates comprising oppositely dis-
posed abutments for engaging the barrel to
secure the plates against rotation, grooves in
the spindle in which the oppositely disposed

key-engaged abutments are slidable radially; 50 and means for holding the plates in face to face engagement in the barrel.

13. A lock comprising a fixed barrel, a rotatable spindle having a key way therein, a series of tumbler plates, each provided with a pair of oppositely disposed abutments adapted respectively to be engaged by a key to shift the tumbler plates in opposite directions, each tumbler being cut away around the spindle, and provided with locking abutments varying in length in accordance with the contour of the key, so that when the key has been inserted in the spindle, the outer ends will be alined, the barrel being provided with means for receiving the locking abutments when they are out of alinement. 55 60 65

14. A lock comprising a fixed barrel, a rotatable spindle having a key way therein, a series of tumbler plates, each provided with a pair of oppositely disposed abutments adapted respectively to be engaged by a key to shift the tumbler plates in opposite directions, each tumbler being cut away around the spindle, provided with locking abutments varying in length in accordance with the contour of the key, so that when the key has been inserted in the spindle, the outer ends will be alined, the barrel being provided with means for receiving the locking abutments when they are out of alinement and adjustable means for holding the tumblers in face to face and sliding engagement. 70 75 80

15. A lock comprising a fixed barrel, a 85
spindle rotatable therein and having a key
way formed therein, a series of tumbler
plates, each provided with a pair of oppo-
sitely disposed abutments adapted respect-
ively to be engaged by a key, locking means 90
between the tumblers and the barrel, some of
the tumblers being provided with extensions,
and a bolt connected to and operated by said
extensions.
